UNITED STATES PATENT OFFICE.

ARTHUR W. NELSON, OF WILLIAMSPORT, PENNSYLVANIA.

SASH-CORD FASTENER.

Application filed September 1, 1921. Serial No. 497,602.

To all whom it may concern:

Be it known that I, ARTHUR W. NELSON, a citizen of the United States, residing at Williamsport, in the county of Lycoming and State of Pennsylvania, have invented 5 certain new and useful Improvements in Sash-Cord Fasteners; and I do declare the following to be a full, clear, and exact description of the invention, such as will enable others skilled in the art to which it 10 pertains to make and use the same.

This invention relates to an improved sash cord fastener and one object of the invention is to provide a cord fastener which is 15 so constructed that it may serve not only to connect the sash cord with the sash but also serve as means for preventing the window from rattling.

Another object of the invention is to so 20 construct this sash cord fastened that the weight of the sash weight will serve to hold a roller in engagement with the window frame so that the sash will be firmly held against rattling but permitted to be easily 25 raised or lowered.

Another object of the invention is to provide a sash cord fastener which is so constructed that a sash cord of the chain type may be easily connected with the fastener 30 and readily disconnected from the same when desired.

This invention is illustrated in the accompanying drawings, wherein:

Figure 1 is a vertical sectional view 35 through a window structure having the upper and lower sashes provided with the improved cord fasteners, the view being taken along the line 1—1 of Fig. 2.

Figure 2 is a vertical sectional view taken 40 along the line 2—2 of Fig. 1.

Figure 3 is a transverse sectional view 45 through a window structure having the cord fasteners connected with the sashes.

Figure 4 is an enlarged view showing the 50 fastener in elevation and applied to a window sash.

Figure 5 is a view in elevation showing 55 the structure of Fig. 4 viewed from the right.

This improved device is to be used in 60 connection with the upper and lower sashes 1 and 2 of a window. These sashes 1 and 2 are slidably mounted in the window frame 3 between the strips or spacing beads 4 and 65 these sashes will be provided with the usual weights 5 carried by flexible carriers shown

in the present illustration as chains 6 which pass over pulleys 7. So far the structure is a conventional window structure.

In order to connect the weight carrying 60 chains 6 with the sashes 1 and 2, each of the sashes will have each side bar cut out to provide a pocket 8 which is positioned at the lower end of a groove 9 which is cut from the upper end of the sash. A plate 10 is 65 positioned in the pocket 8 and is secured by screws 11. This plate 8 carries a lever 12 which is of the bell-crank type and is pivotally connected with the plate 10 by means of a post 13, the outer end portion of which 70 is enlarged to retain the lever upon the post. This lever 12 has its horizontal arm terminating in a hook 14 for engaging the end of the weight carrying chain 6 and has its vertical arm carrying a stem or axle 15 upon 75 which is rotatably mounted a roller 16. From an inspection of Fig. 5, it will be readily seen that when the chain 6 is connected with the hook 14, the weight of the window weights 5 will cause this lever to 80 be held in a position with the roller engaging one of the beads 4. The pressure of the rollers against the beads will cause the window sash to be forced in close contact with a second bead and this will prevent the window from rattling. It will thus be seen that 85 the device serves as means for connecting the weight carrying chain with the window sash and also serves as means for preventing the window sash from rattling. It 90

should be noted that the plates are positioned approximately midway the height of the window sash and therefore the pressure of the rollers will be evenly applied and the window sash will be held against rattling 95 in a very efficient manner. By drawing the lower sash forwardly when moving it upwardly and by moving the upper sash rearwardly when drawing it downwardly to an open position, the sashes can be easily moved as this will do away with a portion of the frictional binding between the window sash and frame. When it is desired to remove a window sash from the frame and it is necessary to disconnect the chains 6, it is simply necessary to unhook the chains from the hooks 14.

I claim:

1. A window structure comprising a frame, a sash slidably carried by said frame, 110 suspending means for said sash including a flexible carrier, and engaging means car-

ried by the central portion of said sash and including a pivoted element engaged by the carrier and moved by the action of the suspending means into engagement with the frame to hold the sash against rattling and exclude weather.

2. The structure of claim 1 having said element pivoted intermediate its length and provided with carrier engaging means at one end and a frame engaging element at the other end.

3. The structure of claim 1 having the said element in the form of a bell crank lever pivotally mounted at the junction of its arms having one arm provided with carrier engaging means, and a frame engaging roller carried by its second arm.

4. A window structure comprising a frame provided with a pair of window stops, a sash slidably mounted between said stops, a weight, a weight carrying chain, and means for connecting the weight chain with the sash, said means including a bell crank lever pivotally mounted on said sash and having a horizontal arm connected with the chain and a vertical arm provided with a roller for engaging one of said stops and moving the sash into engagement with the other of said stops when the lever is moved by the action of said weight.

5. A window structure comprising a frame provided with a pair of window stops, a sash slidably mounted between said stops

and intermediate its height having its side edges provided with recesses forming seats having shoulders at their upper and lower ends, weights, weight-carrying chains, and means for connecting the weight carrying chains with said sash, said means each comprising a plate secured in one of said seats with its ends engaging the shoulders at the upper and lower ends of the seat, a bell crank lever pivotally connected with said plate and having a horizontal arm and a vertical arm, the horizontal arm terminating in a hook portion engaging said chain, and a roller carried by the vertical arm and engaging one of the stops to move the sash into engagement with the other stop and hold the sash against rattling when the lever is moved in an operative direction.

6. A sash cord fastener comprising a plate adapted to be secured to the side edge of a window sash, a bell crank lever pivotally mounted on said plate, one arm of said lever being provided with means for engaging a sash cord and a roller carried by the other arm of said lever and adapted to engage the side of a window stop when the sash cord fastener is secured to the edge of a sash, and the first mentioned arm of the bell crank lever is connected with the sash cord.

In testimony whereof I have hereunto set my hand.

ARTHUR W. NELSON.
